UNITED STATES PATENT OFFICE.

HEYWARD SCUDDER, OF BOSTON, MASSACHUSETTS.

HOLDER FOR CARD-INDEXING CARDS.

SPECIFICATION forming part of Letters Patent No. 757,686, dated April 19, 1904.

Application filed May 1, 1903. Serial No. 155,130. (No model.)

To all whom it may concern:

Be it known that I, HEYWARD SCUDDER, a citizen of the United States, residing at Boston, in the county of Suffolk and State of Massachusetts, have invented certain new and useful Improvements in Holders for Card-Indexing Cards, of which the following is a specification, reference being had therein to the accompanying drawings.

10 Figure 1 represents a plan view of holder containing cards. Fig. 2 represents a sectional view of holder with cards along line 2 2. Fig. 3 represents a sectional view along line 3 3.

15 The object of my invention is to produce a series of movable independent index-cards arranged edgewise one above another, so that a number of such cards may be seen at a glance on a flat surface, the cards being removably secured in any suitable holder and means being provided to prevent the cards from slipping over or past one another when so arranged.

20 In the drawings, 1 is a form of holder, in this instance made of a backing of sheet material and having a fixed edge flap 2, which overlaps corresponding ends of the index-cards 4. The backing is also provided with corner-flaps 5 at the corners opposite that edge which is provided with the flap 2, these corner-flaps 5 overlapping the backing. Intermediate the corner-flaps 5 there is a flap 6, which overlaps the backing.

25 When cards 4 are in place in the holder with corresponding ends under flap 2, their outer ends extend toward the corner-flaps 5 and flap 6. To hold the cards in place, the removable holding-strip 7 is inserted with its end under the corner-flaps and its outer edge 30 under the flap 6, its inner margin then lapping the card ends opposite the ends which are under flange 2. This is a good form of holder, which may be fastened, for example, to the

inside of a book-cover. If it is desired to index a given book, this mode of use is convenient; but my invention is capable of many other modes of use.

35 My invention requires provision for insertion, removal, and rearrangement of the index-cards one in relation to another, and the cards when in place must be kept from slipping past one another. Accordingly I slit a long margin of a card inwardly, as at 10 10, thus forming a tongue 11 on a long edge of each card. When the cards are in the holder, the tongue 11 of one card overlaps the opposed margin of the next card, an edge of which is thus socketed at the bottoms of the slots. This construction is merely one way of preventing the cards from becoming displaced by 40 slipping past one another when in proper position in the holder and of holding the cards in proper relative positions. This construction, in effect, secures a detachable interlocking of the index-cards; but any other desired way 45 of keeping the cards flatwise in relation to the holder and edgewise in relation one to the other may be used.

50 What I claim is—

1. The combination of an index-card holder with a series of detachably-interlocking index-cards mounted flatwise therein, in edgewise relation, one to another; and means for preventing the cards from slipping past one another when in place.

2. The combination of an index-card holder; and a series of detachably-interlocking index-cards arranged flatwise in the holder and edgewise in relation one to another.

3. In testimony whereof I affix my signature in presence of two witnesses.

HEYWARD SCUDDER.
